UNITED STATES PATENT OFFICE

104,116

DESIGN FOR A STATUETTE OR SIMILAR ARTICLE

Jane Miller, New York, N. Y.

Application January 18, 1937, Serial No. 67,110

Term of patent 7 years

To all whom it may concern:

Be it known that I, Jane Miller, a citizen of the United States of America, residing at 163 East 36th Street, in the Borough of Manhattan, city, county, and State of New York, have invented a new, original, and ornamental Design for a Statuette or Similar Article, of which the following is a specification, reference being had to the accompanying drawing, forming a part thereof, and showing a perspective side view of the statuette embodying my design.

I claim:

The ornamental design for a statuette or similar article, substantially as shown.

JANE MILLER.
